WILLARD H. SMITH AND JOSEPH STEGER, OF NEW YORK, N. Y.

Letters Patent No. 74,860, dated February 25, 1868.

IMPROVED CAR-BRAKE.

The Schedule referred to in these Letters Patent and making part of the same.

TO ALL WHOM IT MAY CONCERN:

Be it known that we, WILLARD H. SMITH and JOSEPH STEGER, of the city, county, and State of New York, have made new and useful Improvements in Car-Brakes; and we do hereby declare the following to be a full and exact description of the same, sufficient to enable others skilled in the art to which our invention appertains to understand and use the same, reference being had to the accompanying drawings, which make part of this specification, and in which—

Figure 1 is a bottom view of a car-truck, with my improved brake attached, and

Figure 2 is a detached view of the rotating-device.

Similar letters of reference indicate corresponding parts in the two figures.

The nature of our invention consists in a novel application of a cam-motion, which is made to act upon rollers attached to the brakes, and by means of which the brakes may be set instantaneously, and with a powerful strain, and less labor than is required in setting the lever-brakes now in common use.

A, in the drawings, may represent the bottom of a car. B B and C C are the wheels, the axles D and E of which are secured in the usual manner. F F' represent the bars, to which the brakes are attached, and which are hung from the bottom of the car A. G G' are hangers, in which are the bearings of the shaft H; these hangers are attached to the bottom of the car A. Secured on the shaft H are the cams I I', either by being keyed on the shaft, or in any other equivalent manner. The cams I I' consist of the straight circular part i, which expands, as shown at i¹, and the cam proper i², a groove, j, being formed between the part i¹ and the cam i². Running in the grooves j, and attached to the same, are the ropes or chains h, which, after passing over horizontal grooved rollers g, are attached to the brake-rods f, by means of which they are operated. Attached to the bars F F' are bearings e e and e' e', for the rollers d d', against which the cams proper, i², operate. One end of straight spring K is securely fastened to the bottom of the car, its free end being connected to either cam on the shaft H by a rope or chain, c, in such a manner, that when the cam has been rotated by means of the brake-rods, and the spring become bent, it will rotate the shaft back to its original position, when the brake-rods are released. Instead of a straight spring, we may use a spiral or any other one, fig. 2 showing an example in which a spiral one is applied. Springs b help to relieve the brakes from the wheels.

The operation is as follows: When the brake-rods f are turned they wind up the chains h, which rotate the cams I I', and as, in the normal condition, the narrowest parts of the cams proper, i², rest against the rollers d d', the cams i² press, as they are rotated, against the rollers d d', and force the brake-bars F F', to which the rollers are attached, against the wheels. It will be easily understood, that by means of our device the brakes will act instantaneously, as the cams proper, i², begin to press the brakes against the wheels as soon as the cams I I' are rotated by the brake-rods f, and it will be as clearly understood, that by the cam-motion a greater and surer power is exerted on the brakes, with much less labor, than is now attained by greater exertion in the lever-motion, as levers are continually liable to spring and become ineffective. Our brakes are equally applicable to railroad-cars, street-cars, and wherever brakes are used.

Having thus described our invention, what we claim as new, and desire to secure by Letters Patent, is—

The combination of the spring K, cams I I', constructed as described, ropes or chains h, and pulleys g, substantially as and for the purposes described.

W. H. SMITH,
JOSEPH STEGER.
